United States Patent

Des. 237,464

Patented Nov. 4, 1975

237,464

FUEL TANK

Russell H. Ciphers, 3272 Country Club Drive,
Medina, Ohio 44256

Filed Feb. 8, 1973, Ser. No. 330,572

Term of patent 14 years

Int. Cl. D9—02

U.S. CL. D9—175

FIG. 1

FIG. 2

FIG. 3

FIG. 4

FIG. 1 is a top perspective view of a fuel tank showing my new design;

FIG. 2 is an end elevational view on a reduced scale;

FIG. 3 is a top plan view on the same scale as FIG. 1; and

FIG. 4 is a bottom plan view thereof.

I claim:

The ornamental design for a fuel tank, substantially as shown.
